UNITED STATES PATENT OFFICE

2,133,818

REFRIGERATING APPARATUS

George E. Hulse, New Haven, Conn., assignor
of one-half to Robert S. Blair, Stamford,
Conn.

Application September 9, 1933, Serial No. 688,792

4 Claims. (Cl. 62—72)

This invention relates to refrigeration.

One of the objects thereof is to provide refrigerating apparatus of simple construction and efficient action. Another object is to provide practical apparatus of the above type in which the refrigerating action is economically controlled. Another object is to provide apparatus of the above type which is of rugged and yet inexpensive construction and which requires a minimum of care in its use. Other objects will be in part obvious and in part pointed out hereinafter.

The invention accordingly consists in the features of construction, combinations of elements, and arrangement of parts all as will be illustratively described and the scope of the application of which will be pointed out in the appended claims.

In the accompanying drawing, in which is shown one of the various possible embodiments of this invention,

Figure 1 is a sectional elevation of a refrigerator;

Figure 2 is a front elevation on a smaller scale with a diagrammatic showing of circuits;

Figure 3 is a sectional view of a switch or cut-out and its controlling parts.

Similar reference characters refer to similar parts throughout the several figures of the drawing.

There is shown at 10 the casing of a refrigerator of the type adapted for domestic use, this casing being provided with heat insulation in its walls as shown at 11.

The interior of this casing is provided with a lower compartment 12 roofed by a dividing shelf 13 which is provided with a port or air passage 14. The upper portion of the refrigerator is subdivided into the spaces 15 and 16 by an upright partition 17 having an air port or passage 18 adjacent its upper end. Suitable vertically adjustable shelves 19 are mounted as shown and are of open work to permit the air to pass readily therethrough, these shelves serving to support the food or other material to be kept cool as indicated at 20.

The casing or housing 10 is mounted upon suitable legs 21 and provided through its lower wall with a drain passage 22.

In the space or compartment 12 there is provided a basket 23, formed of metal screening or like material, which is preferably rigid and provided at its upper edges with flanges 24 respectively resting within the guides 25 which are mounted upon the lower portion of the wall 13. Thus this basket 23 may be slidably moved out-

wardly for the purpose of filling it with ice, and it may be noted that this apparatus is particularly suited for use with broken ice and more especially of the so-called flake form, this being indicated within the basket at 26.

Mounted at the righthand end of the basket, as shown in Fig. 1 of the drawing, is a suction funnel 27 leading to the inlet of a suitable blower 28 which discharges upwardly through the passage 29 into the space above the shelf 13 and at the right hand of the partition 17. Although this blower is indicated as of the centrifugal type, other types of blowers may be employed such as an ordinary suction fan, if desired. The driving shaft 30 of the blower 28 leads to an electric motor 31 positioned as shown externally of the wall of the refrigerator. It may here be noted that by this arrangement the substantial amount of heat generated by the motor is kept outside the refrigerating apparatus, thus greatly enhancing its economy and yet the blower or air driving apparatus is simply and efficiently driven.

The compartments 15 and 16 are respectively closed by separate doors 32 and 33 which swing respectively to the left and to the right, as indicated in Fig. 2 of the drawing. The lower compartment is also provided with a door 34 which in this instance may be swung downwardly to open. All of these doors are formed with suitable heat insulating filling and provided with suitable latches.

It will be seen with the apparatus as thus far described that with the doors closed and the motor 31 in operation the air within the refrigerator is vigorously circulated, being drawn into the blower and discharged upwardly into the space 16, thence passing to the left through the port 18, thence downwardly through the space 15 and the port 14 to the lower compartment. At this point, the passage transversely through this compartment being substantially blocked by the basket 23 and its contents, the air is compelled to travel through the ice within this basket and thus brought intimately into contact with the large exposed surface of the ice. The funnel member 27, which extends substantially to the bottom of the basket as shown, so as to draw air through the ice when the basket is only partially filled, sucks the air into the blower and the above cycle is repeated. There is preferably provided an imperforate partition 27a which extends from the top to a short distance below the bottom of the compartment 12 and forces all air traveling to the blower 28 to pass under its lower edge as indicated by the arrow. By this partition the

air is forced through the ice even though the basket is nearly empty.

Positioned within the above air circuit is the effective portion 35 of a thermostat 36 which, as diagrammatically indicated in Fig. 2 of the drawings, will control the circuit between conductors 37 and 38. This is done by a contact on the thermostat bridging coating contacts as indicated when the thermostat expands to a limit indicating an excess over the temperature desired to be maintained within the refrigerator. This is, of course, adjustable in the well-known way and the connection of these conductors 37 and 38 will lead current to the motor 31, thus connecting the latter across the mains indicated at 39 whenever suitable switches hereinafter described are in closed condition. One of these switches is the hand switch 40 which is assumed to be closed whenever the apparatus is in use.

The doors 32, 33 and 34 are provided respectively with switches 41, 42 and 43, as diagrammatically indicated in Fig. 2 of the drawing, and the construction of a suitable form of these switches is shown in detail in Fig. 3. The door, shown in this figure as door 33, is hinged so as to open into the position as shown in dotted lines in this figure and to close as shown in full lines. The edge portion of the door adjacent the hinge contacts a plunger 44 sliding in a suitable guide 45 in the refrigerator wall and bearing a conducting bridge contact 46 which in its closed position connects the relatively insulated contacts 47 and 48. Thus when all of the doors are closed and the thermostat 36 expanded, the switches 41, 42 and 43, as well as switch 40, will be closed and the motor 31 in operation with the vigorous circulation of the air within the refrigerator as hereinbefore described, it being understood that the partitions 17 and 18 extend from front to back of the refrigerator. If the motor 31 is not in action, it is important to note that even the opening of one of the upper doors would not cause a serious loss of cooled air for the ice with the coldest air is positioned in the lowermost compartment and it is unnecessary to open this except when the supply is to be replenished. This arrangement of the parts conduces to economy in action. If, however, the blower 28 were in operation, the rapid circulation of the air would within a short time cause a serious loss if one of the doors were opened. Accordingly the plunger 44 is provided with a spring 49 which tends to urge it in a direction to break the connection between the contacts 47 and 48 or the corresponding contacts in the remaining switches. Thus as one of the doors is opened the circuit of the motor is instantaneously and automatically broken and the blower stopped. This feature, together with positioning of the refrigerating agent in a usually closed compartment at the bottom prevents any substantial loss of refrigerated air.

The use of the basket for the flake ice or the like not only holds it in position for quick action upon the air but permits it readily to be placed in position by being dumped therein from any suitable container and holds it in position even if the door to the cooling chamber be opened.

It will thus be seen that there is provided apparatus in which the objects of the invention are achieved and which is well suited to the conditions of hard practical use.

As various changes could be made in the above apparatus and as the invention herein described could well be embodied in apparatus which would

be superficially different, it is to be understood that all matter herein described or shown in the accompanying drawing is to be interpreted in an illustrative and not in a limiting sense.

I claim:

1. In refrigerating apparatus, in combination, a casing provided with a horizontal partition having two openings therein, said partition dividing said casing into an upper and a lower compartment, a partition dividing said upper compartment of the casing with said openings in opposite sides thereof and provided with an opening substantially adjacent the top of said casing, means within said lower compartment comprising a basket-like member adapted to support finely divided ice, means adapted to draw air through said basket member and through said ice and circulate the same within said casing, said means including a partition extending downwardly from said horizontal partition whereby the lower edge of said lower compartment partition is spaced from the bottom of said casing, means mounting said basket member adapted to permit it to slide outwardly beyond the boundaries of said casing and expose its upper side for refilling, and a motor adapted to operate said second-mentioned means, said motor being mounted in such manner with respect to said casing that heat generated by the operations of the motor is not dissipated in the path of said air.

2. In refrigerating apparatus, in combination, a casing provided with a horizontal partition having two openings therein whereby said casing is divided into an upper and a lower compartment, a vertical partition secured to said horizontal partition and extending downwardly therefrom whereby the lower edge of said vertical partition is spaced from the bottom of said casing, a basket member adapted to hold finely divided ice slidably mounted in said lower compartment between said vertical partition and one of the side walls of said casing, said basket member being disposed beneath one of the openings in said horizontal partition, a fan element in said lower compartment having its inlet connected to the opening formed by the lower edge of said vertical partition and said casing bottom and having its outlet connected to the other of said horizontal partition openings whereby air is drawn from said upper compartment through said first-mentioned opening and through said finely divided ice and is delivered into said upper compartment by said last-mentioned horizontal partition opening, and means for driving said fan element, said means being mounted in such manner with respect to said casing that heat generated by the operation thereof is dissipated exteriorly of said compartments.

3. In refrigerating apparatus, in combination, a casing provided with a horizontal partition having two openings therein whereby said casing is divided into an upper and a lower compartment, a vertical partition secured to said horizontal partition and extending downwardly therefrom whereby the lower edge of said vertical partition is spaced from the bottom of said casing, a basket member adapted to hold finely divided ice slidably mounted in said lower compartment between said vertical partition and one of the side walls of said casing, said basket member being disposed beneath one of the openings in said horizontal partition, a fan element in said lower compartment having its inlet connected to the opening formed by the lower edge of said

vertical partition and said casing bottom and having its outlet connected to the other of said horizontal partition openings whereby air is drawn from said upper compartment through 5 said first-mentioned opening and through said finely divided ice and is delivered into said upper compartment by said last-mentioned horizontal partition opening, means for driving said fan element, said means being mounted in such manner 10 with respect to said casing that heat generated by the operation thereof is dissipated exteriorly of said compartments, closure members for said compartments, and means adapted to halt the operation of said fan driving means upon said 15 closures being opened.

4. In refrigerating apparatus, in combination, a casing, a horizontal partition dividing said casing into an upper and a lower chamber therein, said partition having openings therein at each lateral end thereof, a vertical partition between 20 said openings dividing said upper chamber into

a plurality of compartments, said vertical partition extending to the top of said casing and having an opening therein adjacent the top thereof, refrigerating means in said lower chamber, an air circulator connected to said refrigerating means and adapted to force cooled air therefrom through one of the openings in said horizontal partition, whereby cooled air is forced into one of said upper compartments, through the opening in the top of said vertical partition, through 10 another of said upper compartments and through the other opening in said horizontal compartment into said lower chamber, a motor for driving said air circulator, said motor being mounted on the outside of said casing, closure means for 15 said upper compartments, and means associated with said casing and operative upon said closure means being opened to halt the operation of said motor to prevent cool air being forced out of said compartments.

20
GEORGE E. HULSE.
